UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

CROSSBAR LINE SWITCH.

Application filed October 14, 1920. Serial No. 416,835.

To all whom it may concern:

Be it known that I, JOHN NEWBERRY REYNOLDS, a citizen of the United States, residing at Greenwich, in the county of Fair-

5 field, State of Connecticut, have invented certain new and useful Improvements in Crossbar Line Switches, of which the following is a full, clear, concise, and exact de-
scription.

10 This invention relates to electric switches of the type used in automatic telephone exchanges for effecting connections between calling subscribers' lines and trunk lines to first selectors or other switching apparatus

15 whereby calls are extended to other sub-
scribers' lines. Switches of the class includ-
ing this invention are known as line switches.
More particularly this invention relates to
that class of line switches designated as the
20 cross bar type.

The object of this invention is the pro-
vision of a commercially practicable cross
bar line switch, that is one which is eco-
nomical to manufacture, which will give
25 continuous and satisfactory service and
which is easily accessible for adjustments,
repairs, and replacements of parts when the
latter become worn.

All cross bar switches, as the name im-
30 plies are characterized, in contradistinction
to other types of line switches, by co-ordin-
ately arranged conducting bars; those bars
extending in one direction being associated
35 with subscribers' lines and those extending
in the other direction with trunk lines. The
subscribers' line bars, or briefly "line bars"
each being arranged in co-ordinate relation
40 to all the trunk bars are adapted to estab-
lish electrical connections with all the trunk
bars individually. In other words, any sub-
scriber's line associated with the switch may
be connected with any trunk line associated
45 therewith.

In ordinary practice, a cross bar line
50 switch is provided with ten or twelve trunk
bars, each of which is associated with a
separate trunk circuit, and one hundred line
bars, each of which is associated with a sub-
scriber's line.

55 This invention does not differ functionally
from the cross bar line switches which have

heretofore been developed, but it does differ
therefrom in certain improvements which
contribute materially to operating efficiency
and economy.

55 One of the improved features of this in-
vention is the provision of means whereby
the line bars can be readily moved out of
operable relation to the trunk bars so that
the latter are made accessible for adjust-
60 ments, repairs and replacements. This ad-
vantage is accomplished by mounting the
line bars in groups on hinged members
which are easily swung into or out of their
normal positions.

65 Another feature resides in the improved
design of the trunk bars, which while pro-
viding a structure which is extremely eco-
nomical to manufacture has an added ad-
70 vantage of no small importance, in that its
contact springs are particularly easy to ad-
just.

75 Still another feature is the arrangement
of the line bars so that they move in a hori-
zontal plane instead of a vertical plane to
establish connections with the trunk bars.
This feature is of advantage because it per-
80 mits mounting the line bar operating mag-
nets more conveniently in the space avail-
able and permits the use of larger magnets
than would otherwise be possible, unless the
line bars were spaced farther apart, which
would of course result in a larger switch.

85 The switch to be described hereinafter as
representative of this invention comprises
twelve vertical trunk bars and one hundred
horizontal line bars. Each trunk bar is
divided into two like parts, but the two
parts operate simultaneously and are con-
90 nected together electrically. They are in
effect one trunk bar and are so considered
in the detailed description hereinafter.
They are arranged in two groups, one above
the other, one half of each trunk bar being
95 in the upper group and the other half in the
lower group.

An operating mechanism for the trunk
bars is situated midway between the two
groups. The function of this operating
mechanism is to select idle trunk bars and
move them into position so that they can be
100 engaged by the line bars, and further to re-

- lease the trunk bars after they have been so engaged. When a trunk bar has been moved into position where it can be engaged by a line bar it is said to be pre-selected or to have been moved into its pre-selected position. The method of pre-selecting the trunk bars in the present instance consists in rotating them through a small angle from their normal positions. Only one trunk bar at a time can be in a pre-selected position. As soon as a trunk bar is engaged by a line bar it must be returned to its normal position, and a succeeding idle trunk bar must be immediately pre-selected.
- 15 The trunk bar operating mechanism described hereinafter is that which is described and claimed in the co-pending application of Arthur C. Magrath, Serial Number 417,068, filed October 15, 1920.
- 20 The line bars are arranged in four groups of twenty-five each, there being two groups of line bars on each side of the switch. The line bars described hereinafter are those which are described and claimed in the co-pending application of Arthur C. Magrath, Serial Number 417,428, filed October 16, 1920.
- 25 Referring to the drawings herewith: Fig. 1 is a perspective view showing the assembled switch. This view particularly illustrates the hinged mountings for the line bars. The lower group of trunk bars is shown in this view, the upper group being concealed by the line bars. The trunk bar operating mechanism is shown in a general way situated between the two groups of trunk bars. The electro-magnets for operating the line bars are shown situated in a vertical row on the right hand side of the switch. Fig. 2 is a fragmentary cross-sectional view showing four trunk bars; one line bar with the hinged member on which it is mounted (the hinged portion being broken away), and two electro-magnets for operating line bars. Fig. 3 is a cross sectional view along the line 3—3 of Fig. 5, illustrating particularly the trunk bar operating mechanism. Fig. 4 is an elevational view taken at the left hand end of Fig. 3, showing the trunk selecting commutator and the motor magnet for rotating the trunk bar operating mechanism. Fig. 5 is a sectional view along the line 5—5 of Fig. 3, illustrating the trunk bar operating mechanism, Fig. 6 is an elevation of the middle portion of the switch on the side thereof opposite the trunk bar operating mechanism as indicated by the line 6—6 of Fig. 5. Fig. 7 is a perspective view of a portion of a line bar.

Each trunk bar, as previously stated comprises two like sections, one of which is situated in the upper group and the other in the lower group. This is illustrated in Fig. 5, 65 which shows the lower end of an upper

trunk bar section and the upper end of a lower trunk bar section. The two sections operate simultaneously. That is they rotate at the same time. Each section is centrally pivoted at its two ends.

70 Each trunk bar section comprises four flat strips of spring metal 1, each of which has fifty laterally extending spring-arms 2, 3, 4 and 5. Twenty-five of the spring arms extend from each side of the respective strips. The spring-arms 2 are all integral with one strip, 3 are integral with another strip, etc. The strips are superposed and insulated from each other and are attached to the supporting member of the trunk bar by means of bolts 12. The spring-arms are arranged in groups as shown in Fig. 5, each group being associated with a line bar.

75 A strip of insulating material 13 having a flat edge against which the spring-arms normally bear, is situated near the ends of the spring-arms. This strip holds the spring-arms in a common plane.

80 With the arrangement described wherein the spring-arms are situated side by side instead of being superposed one upon the other as has heretofore been customary, adjustment of the individual spring-arms is facilitated in that the adjusting of each spring-arm is entirely independent of and does not interfere with the adjustment of the others.

85 The line bars, each comprise four strips of metal 6, 7, 8 and 9, each of which is provided with thirteen contact members 10. Twelve of these contact members are each associated with a spring-arm of a trunk bar and the other contact member is associated with a contact spring 11. When a line bar is in normal position as shown in Fig. 2, none of its contact members 10 are engaged.

90 The line bars are each pivotally mounted on links 14 which in turn are pivotally mounted on brackets 15, which are attached to the hinged members 40. Springs 16 hold the line bars in their normal positions when 95 they are not otherwise displaced.

95 Associated with each line bar is an electro-magnet 19 which has an armature 18 to which is attached an arm 17. The latter engages the line bar and upon energization 115 of electro-magnet 19 moves the line bar out of its normal position through an arcuate path indicated by the arrows in Fig. 2. It will be seen that the ends of the spring-arms of the second trunk bar from the right in Fig. 2 intercept the paths of these associated contact members 10. This trunk bar is in its pre-selected position, having been rotated from its normal position parallel to the other trunk bars shown. The ends of 120 the spring-arms of the other trunk bars in Fig. 2, it will be seen do not intercept the paths of their associated contact members 10. Contact springs 11 are not rotatable—they make contact with their associated con- 125

tact members 10 each time the line bar is operated, regardless of which trunk bar is engaged.

An individual subscriber's line being connected with each set of contact springs 11, it follows that, through the medium of the associated line bars, each subscriber's line may be connected with any trunk terminating in the switch.

10 The lower end of each upper trunk bar section and the upper end of each lower trunk bar section is provided with a laterally extending arm 21 which co-operates with the trunk bar operating mechanism to rotate the trunk bars into their pre-selected positions. A spring 22 bears against arm 21 and retains the trunk bar in its normal position when it is not otherwise displaced.

15 The trunk bar operating mechanism comprises a shaft 23 journaled in bearings 37 and 38. The shaft is rotatable and moveable longitudinally, in the bearings. A spring 39 is provided for holding the shaft in its normal longitudinal position as shown 20 in Fig. 3 and for returning it to that position after it has been displaced. A ratchet 27 mounted on shaft 23 is engaged by pawl 28 carried by armature 29 of motor magnet 30, which operates to rotate the shaft.

25 30 Mounted on shaft 23 at equal intervals are twelve discs 24, one for each trunk bar. These discs are both rotatable and movable longitudinally with the shaft. Each disc is provided with two lugs 25 situated diametrically opposite each other, and two slots 26 also diametrically opposite and at right angles to the lugs.

35 The lugs 25 of the several disks are situated in different angular positions around the shaft as shown in Fig. 5.

40 The lugs of each disc are adapted upon longitudinal movement of the shaft to engage the arms 21 with which they are associated and thereby to rotate the trunk bar into its pre-selected position. It is only when the lugs are in juxtaposition to their 45 associated arms 21, however, that they can engage them and since only one pair of lugs is so situated at any one time, it is 50 obvious that only one trunk bar can be pre-selected at a time.

A latch member 35 clearly disclosed in Fig. 5 is provided for each trunk bar. It is pivotally mounted on pin 39 and is provided with a spring 41 which tends to hold 55 it in its normal position.

When the trunk bar is pre-selected, the latch engages the lug 42 on the arm 21 and holds the bar in its pre-selected position 60 until it is released as will be explained.

A finger 36 attached to or integral with each latch member 35 projects into the path of its associated disc 24. When the lugs 65 25 are in position to engage arms 21, one of the slots 26 is in position to clear finger

36, but when the disc is in any other position it will engage finger 36 upon longitudinal movement of the shaft and move it together with latch member 35 to release the trunk bar.

70 Immediately following the pre-selection of a trunk bar, shaft 23 is rotated until a pair of lugs are situated in operable relation to the arms 21 of the next succeeding idle trunk. The shaft then remains stationary until, in response to the next subscriber's call, the pre-selected trunk bar is engaged by a line bar. This is immediately followed by energization of electro-magnet 33, which draws up its armature 34 thereby 80 imparting a longitudinal movement to shaft 23. This longitudinal movement of the shaft effects the release of the pre-selected trunk bar and simultaneously moves the next idle trunk bar into its pre-selected 85 position.

85 The commutator shown in Fig. 4, comprises a plurality of stationary terminals 32, each associated with a trunk. Brush 31 mounted on shaft 23 and rotatable therewith is adapted to make successive contact with terminals 32. Brush 31 is included in the circuit of electro-magnet 30. Whenever brush 31 makes contact with a terminal 32 which is associated with a busy trunk, there is a circuit established through electro-magnet 30 which causes it to operate its armature thereby rotating shaft 23. Shaft 23 is thus rotated until a terminal associated with an idle trunk is located by brush 31, at 90 which time the pair of lugs 25 associated with that idle trunk are also in operable relation with their associated arms 21.

95 The contact springs shown in Fig. 6 are operated in response to movements of the 105 trunk bars, but inasmuch as we are not concerned here with the circuits, but only with the mechanical structure no description of operation of these contact springs will be given.

110 What is claimed is:

1. In a line switch, a plurality of vertical trunk bars, each trunk bar comprising a plurality of sets of contact spring arms all of said contact spring arms normally situated in a common plane, a plurality of line bars, each line bar comprising a plurality of sets of laterally projecting contact members, one for each trunk bar, means for displacing said trunk bars individually to position said contact spring arms thereon in operable relation to said line bar, means for moving said line bars horizontally through an arcuate path to establish connections between said contact members and the contact spring 115 arms of displaced trunk bars. 120

2. A line switch comprising a plurality of vertical trunk bars, a plurality of horizontal individually operable line bars co-operatively associated with said trunk bars 125 130 135

- and a hinged member on which said line bars are mounted.
3. A line switch comprising a plurality of vertical trunk bars, a plurality of horizontal individually operable line bars cooperatively associated with said trunk bars and a hinged member, on which said line bars are mounted, arranged to swing horizontally away from said trunk bars.
- 10 4. A line switch comprising a plurality of vertical trunk bars, a plurality of groups of line bars cooperatively associated with said trunk bars, a hinged member for one of said groups of line bars arranged to move said group out of operable relation to its associated trunk bars, and means individual to each line bar of said group for moving it into operable relation to its associated trunk bar.
- 20 5. In a switching mechanism, a supporting frame, a field of contact sets comprising two groups of contacts cooperatively associated, the contacts of one of said groups being divided into sections, means for removably mounting said sections of contacts on said frame, and means comprising coordinate bars operating conjointly for operating said contact sets.
- 30 6. In a switching mechanism, a supporting frame, a field of contact sets comprising two groups of contacts cooperatively associated, the contacts of one of said groups being divided into sections, a member for supporting each of said sections of contacts, means for removably attaching said members to said frame and means comprising coordinate bars operating conjointly for operating said contact sets.
- 40 7. In a switching mechanism, a supporting frame, a field of contact sets comprising a plurality of contacts arranged in horizontal rows and a plurality of contacts arranged in vertical rows, said horizontal rows of contacts being divided into sections separately supported upon said frame, and means comprising coordinate bars operating conjointly for operating said contact sets.
- 45 8. In a switching mechanism, a supporting frame, a field of contact sets comprising two groups of contacts cooperatively associated, the contacts of said groups being divided into sections, means for removably mounting certain of said sections of contacts on said frame, and means comprising coordinate bars operating conjointly for operating said contact sets.
- 50 9. A trunk bar comprising a plurality of conductor strips superposed and insulated one from the other, a plurality of contacting members extending laterally from each of said conductor strips and integral therewith, and a member having a straight portion against which said contacting members bear, the free ends of said contacting members being thereby normally held in a common plane.
- 55 10. A trunk bar comprising a plurality of conductor strips superposed and insulated one from the other, two groups of contact members each extending laterally in opposite directions from each of said conductor strips, and an aligning member for each group against which the contact members bear, the free ends of the contact members of each group being thereby normally held in a common plane.
- 60 In witness whereof I hereunto subscribe my name this 9th day of October, A. D., 1920.
- 70 JOHN NEWBERRY REYNOLDS.
